UNITED STATES PATENT OFFICE.

PENNY S. McMILLON, OF QUINLAN, TEXAS.

HANGER FOR SLIDING DOORS.

Application filed July 3, 1923. Serial No. 649,272.

To all whom it may concern:

Be it known that I, PENNY S. McMILLON, a citizen of the United States, residing at Quinlan, in the county of Hunt and State 5 of Texas, have invented certain new and useful Improvements in Hangers for Sliding Doors, of which the following is a specification.

My invention relates to an improvement 10 in sliding door hangers and the primary object thereof is the provision of such hanger wherein a swinging movement of the doors to and from the building will be overcome which is now a disagreeable feature 15 with sliding doors of garages, barns and the like.

A further object of the invention is the provision of such a hanger wherein the doors may be easily and expeditiously slid 20 to opened and closed positions without any liability of the same becoming jammed.

A still further object is to provide a hanger for sliding doors that is comparatively simple of construction and one that 25 may be installed in a simple and inexpensive manner.

The nature and advantages of the invention will be better understood when the following detailed description is read in 30 connection with the accompanying drawings, the invention residing in the construction, combination and arrangement of parts as claimed.

In the drawings forming part of this application, like numerals of reference indicate similar parts in the several views, and wherein:

Figure 1 is an elevation of the interior of a building the doors thereof being shown 40 as supported upon my improved hanger.

Figure 2 is a detail longitudinal cross-section taken substantially upon the line 2-2 of Figure 1 and looking downwardly in the direction of the arrows.

Figure 3 is an enlarged fragmentary vertical cross-section taken upon the line 3-3 of the same figure.

Figure 4 is a fragmentary elevation of the inner side of one of the door members 50 equipped with certain elements embodied in my improved hanger.

Figure 5 is a detail vertical cross-section upon the line 5-5 of Figure 1, and

Figures 6, 7 and 8 are perspectives of 55 certain of the elements included in my improved hanger.

Referring to the drawings, 5 indicates a building such as a barn, garage and the like that is provided with a door opening 6, the edges of which are reenforced by 60 metallic plates 7.

Extending across the upper edge of this door opening 6 is a longitudinal bar 8 the opposite ends of which are bent inwardly and are provided with plates 9 that are 65 bolted or otherwise secured to the inside of the building.

The sliding doors are designated 10-10 and upon the upper end of each and at opposite sides thereof are vertically directed straps 11 each of which carries a roller 12 that rides upon the upper surface of the bar 8 and support said doors 10-10 in such a manner as to allow the free sliding movement of the same. Upon the bar 8 and at 70 a point substantially intermediate the ends thereof is an abutment 13 for limiting the sliding movement of the doors 10-10 in certain directions.

Upon the front sides of the doors 10-10 and adjacent the lower outer corners thereof are bracket plates 14 bolted or otherwise suitably secured thereto. As more clearly shown in Figure 7, these bracket plates 14 are formed at their outer ends 75 with forwardly directed extensions 15 that have close contact with the adjacent edges of the doors and are also secured thereto through the medium of screws or the like.

In horizontal alinement with these brackets 14 upon the said doors 10-10 are other bracket plates 16. The bracket plates 14 and 16 are formed with outwardly extending alined eye members 14' and 16', respectively, that receive the opposite ends of 80

horizontal bars 17. The opposite sides of the door opening 6 are equipped adjacent their lower ends and directly rearwardly of the bars 17-17 with bracket plates 18, the inner ends of which are formed with 85

outwardly directed extensions 19 that fit within mortises formed in the sides of the door opening. The bracket plates 18 are formed upon their inner sides with loop element 20 through each of which is engaged 90

the respective rod 19 of its respective door 10.

105

The doors 10-10 may be maintained in closed position through the medium of a desirable form of lock 21 and in view of the 110 above description when considered with the accompanying drawings the operation and

advantages of a hanger for sliding doors of this character will be readily appreciated by those skilled in the art and although I have herein set forth the preferred embodiment of my invention it is nevertheless to be understood that minor changes may be made therein without departing from the spirit and scope of the invention as claimed.

Having described my invention, what I claim and desire to secure by Letters-Patent, is:—

In combination with a body having a door opening, a track rail disposed transversely and above the door opening, door panels having carriages adapted to travel upon said rail, bracket plates mounted at

the sides of the panels and at the inner edges thereof and having eyes alined with each other, bracket plates mounted upon the body at the side edges of the door opening and provided upon their outer sides with vertically disposed loops and a bar fitting snugly in the eyes of the bracket plates and having end portions adapted to enter the loops whereby the door panels and the rods may move vertically with relation to the body but are restrained against outward movement with relation to the body.

In testimony whereof I affix my signature.

PENNY S. McMILLON.
